LIQUID DISPENSING JAR

Louis E. Pastorius III, 2133 Brownsville Road,
Pittsburgh, Pa. 15210

Filed Jan. 26, 1965, Ser. No. 83,576

Term of patent 14 years

(Cl. D58—25)

Fig. 1.

Fig. 2.

Fig. 3.

Fig. 4.

FIG. 1 is a top plan view of a liquid dispensing jar, showing my new design;

FIG. 2 is a front perspective view thereof;

FIG. 3 is a front elevational view thereof;

FIG. 4 is a side elevational view thereof.

The side not shown is a mirror image of the side shown with the broken line showing of a pouring spout being omitted and the back is plain and unornamented.

The dominant features of my design reside in the portions shown in full lines.

I claim:

The ornamental design for a liquid dispensing jar, substantially as shown and described.
